UNITED STATES PATENT OFFICE.

ORLANDO W. CRAMPTON, OF PITTSBURGH, PENNSYLVANIA.

GAME.

1,144,529.

Specification of Letters Patent. Patented June 29, 1915.

Application filed May 29, 1914. Serial No. 841,819.

To all whom it may concern:

Be it known that I, ORLANDO W. CRAMPTON, a citizen of the United States, residing at Pittsburgh, in the county of Allegheny 5 and State of Pennsylvania, have invented certain new and useful Improvements in Games, of which the following is a specification.

This invention relates to improvements in 10 games and has for its object to provide a combined ten-pin alley and bagatelle board.

Another object of the invention is to provide an interchangeable game board.

Another object of the invention is to provide 15 in combination with a ten-pin alley, a ball-directing device.

With the above and still other objects in view which will be further and more fully explained, I have invented the device illustrated in the accompanying drawings in which—

Figure 1, is a top plan view of my game device. Fig. 2, is a section on line A—A of Fig. 1. Fig. 3, is a view similar to Fig. 1, 25 with the bottom of the board reversed. Fig. 4, is a sectional view on line B—B of Fig. 3.

Like reference characters indicate like parts throughout the specification and in the several views in the drawings in which 30 1, indicates my combination game board which consists of a frame member 2, which embraces the vertical walls 3, 4, 5 and 6 having inner right angular horizontal flanges 7, 8, 9 and 10.

A board 11, has a surface 12, which is 35 of a size to exactly fit into the frame 2, and contact all of the walls 3, 4, 5, and 6. This board 11, has its central portion 17, formed considerably thicker than its outer edges 13,

40 14, 15 and 16, said central portion being adapted to project through the opening 18, between the flanges 7, 8, 9 and 10. The end 19, of said central portion is provided with pockets 20, adapted to receive balls 21,

45 22, which are shot toward said pockets 20, by a ball 22, which is projected at the balls 21, through the inclined tube 23, one end of which rests upon the stand 24, and the lower end 25, of which rests upon the

50 edge 26, of the wall 3. Slidably projecting through the openings (not shown) in the walls 4 and 6, is a guide 27, having a ring 28, to receive said end 25, and handles 29 and 30, whereby the said lower end may 55 be directed toward any part of the board 11, desired. The object is to shoot the ball 22

at the balls 21, and cause them to fall into the pockets 20. With three shots at three balls, each time it may be possible to fill all of the pockets 20.

Slides 31, are adapted to be drawn part way from their sockets 32, against the flanges 7 and 9, and the board 11 and the flanges 7 and 9, are fixedly locked together.

By reversing the board 11, so as to cause 65 the portion 17, to project up as indicated in Fig. 3, a ten-pin alley is formed, the pins 33, seating upon the surface 34, the ball 35, being adapted to fall from said surface 34 into each of the channels 36 or 37.

The ten-pin game is played in the usual 70 way with the exception of the manner of projecting the balls which is by gravity through the tube 23.

It may be found desirable in playing the 75 bagatelle game to have the mouth 38, of the tube 23, come nearer to the surface 17, so recesses 39, are provided in the edge 40, of the wall 5, to receive the lower end 25, of the tube 23, in which the position of the 80 board 11, in the frame 2, is reversed the pockets 20, being near the wall 3. The stand 24, consists of a base 41, and a pair of telescopic members 42 and 43, which frictionally engage one another whereby the 85 raising and lowering the member 43, the force with which a ball is shot from the tube 23, may be regulated, the arrangement of the board and ball projection being such that either of the games, ten-pins or bagatelle, may be played thereon with a great 90 deal of skill according to the practice and judgment of the player.

Having now described my invention, that 95 which I claim as new and desire to secure by Letters Patent is:—

1. A game apparatus consisting of a frame having an opening and a supporting rim around said opening, a relatively thick board having playing surfaces adapted to fit into said frame, said board having a flange reduced in thickness to engage the walls of said frame whereby the board will be held centered in the frame.

2. A game apparatus consisting of a frame 105 having an opening and a supporting rim around said opening, a relatively thick board having playing surfaces adapted to fit into said frame, said board being reversible and having a flange to engage the walls 110 of said frame whereby the board will be held centered in the frame, said board hav-

ing an offset which in conjunction with said walls form channels when the offset side is uppermost.

3. A game apparatus consisting of a frame 5 having an opening and a supporting rim around said opening, a relatively thick board having playing surfaces adapted to fit into said frame, said board having a flange to engage the walls of said frame whereby the 10 board will be held centered in the frame, said board having an offset which in conjunction with said walls form channels when the offset side is uppermost, said offset adapted to engage the rim of said opening when the flanged side of the board is 15 uppermost.

4. A game apparatus consisting of a frame having an opening and a supporting rim around said opening, a relatively thick board having playing surfaces adapted to fit into said frame, said board having a flange to engage the walls of said frame whereby the board will be held centered in the frame, said board having an offset which 20 in conjunction with said walls form channels when the offset side is uppermost, said offset adapted to engage the rim of said opening when the flanged side of the board is uppermost, said flanged side having a series of pockets formed therein.

5. A game apparatus consisting of a frame having an opening and a supporting rim around said opening, a relatively thick board having playing surfaces adapted to fit 25 into said frame, said board having a flange to engage the walls of said frame whereby the board will be held centered in the frame, said board having an offset which in conjunction with said walls form channels when the offset side is uppermost, said offset adapted to engage the rim of said opening when the flanged side of the board is uppermost, said flanged side having a series of 30 pockets formed therein, a ball and projector therefor adapted to project balls into said pockets.

6. A game apparatus consisting of a frame having an opening and a supporting rim around said opening, a relatively thick board 35 having playing surfaces adapted to fit into said frame, said board having a flange to engage the walls of said frame whereby the board will be held centered in the frame, said board having an offset which in conjunction with said walls form channels when the offset side is uppermost, said offset adapted to engage the rim of said opening when the flanged side of the board is uppermost, said flanged side having a series of 40 pockets formed therein, a ball and projector therefor adapted to project balls into said pockets, said projector consisting of an inclined tube.

7. A game apparatus consisting of a frame having an opening and a supporting

rim around said opening, a relatively thick board having playing surfaces adapted to fit into said frame, said board having a flange to engage the walls of said frame whereby the board will be held centered in the frame, said board having an offset which in conjunction with said walls form channels when the offset side is uppermost, said offset adapted to engage the rim of said opening when the flanged side of the board is uppermost, said flanged side having a series of pockets formed therein, a ball and projector therefor adapted to project balls into said pockets, said projector consisting of an inclined tube, said projector being pivotally mounted.

8. A game apparatus consisting of a frame having an opening and a supporting rim around said opening, a relatively thick board having playing surfaces adapted to fit into said frame, said board having a flange to engage the walls of said frame whereby the board will be held centered in the frame, said board having an offset which in conjunction with said walls form channels when the offset side is uppermost, said offset adapted to engage the rim of said opening when the flanged side of the board is uppermost, said flanged side having a series of pockets formed therein, a ball and projector therefor adapted to project balls into said pockets, said projector consisting of an inclined tube, said projector being pivotally mounted, means for directing the aim of said tube.

9. A game apparatus consisting of a frame having an opening and a supporting rim around said opening, a relatively thick board having playing surfaces adapted to fit into said frame, said board having a flange to engage the walls of said frame whereby the board will be held centered in the frame, said board having an offset which in conjunction with said walls form channels when the offset side is uppermost, said offset adapted to engage the rim of said opening when the flanged side of the board is uppermost, said flanged side having a series of pockets formed therein, a ball and projector therefor adapted to project balls into said pockets, said projector consisting of an inclined tube, said projector being pivotally mounted, means for directing the aim of said tube, said means consisting of a 110

offset adapted to engage the rim of said opening when the flanged side of the board is uppermost, said flanged side having a series of pockets formed therein, a ball and projector therefor adapted to project balls into said pockets, said projector consisting of an inclined tube, said projector being pivotally mounted, means for directing the aim of said tube, said means consisting of a 10 slidable member, and means thereon for engaging said tube.

11. A game apparatus consisting of a frame having an opening and a supporting rim around said opening, a relatively thick board having playing surfaces adapted to fit into said frame, said board having a flange to engage the walls of said frame whereby the board will be held centered in the frame, said board having an offset which 15 in conjunction with said walls form channels when the offset side is uppermost, said offset adapted to engage the rim of said opening when the flanged side of the board is uppermost, said flanged side having a series of pockets formed therein, a ball and projector therefor adapted to project balls 20 into said pockets, said projector consisting of an inclined tube, said projector being pivotally mounted, means for directing the aim of said tube, said means consisting of a slidable member, and means thereon for engaging said tube, a pivoted stand for said tube.

12. A game apparatus consisting of a frame having an opening and a supporting rim around said opening, a relatively thick board having playing surfaces adapted to fit into said frame, said board having a flange to engage the walls of said frame 35 whereby the board will be held centered in the frame, said board having an offset which in conjunction with said walls form channels when the offset side is uppermost, said offset adapted to engage the rim of said 40 opening when the flanged side of the board is uppermost, said flanged side having a series of pockets formed therein, a ball and projector therefor adapted to project balls 45 into said pockets, said projector consisting of an inclined tube, said projector being pivotally mounted, means for directing the aim of said tube, said means consisting of a slidable member, and means thereon for engaging said tube, a pivoted stand for said 50 tube, said stand being vertically adjustable.

13. A game apparatus consisting of a frame having an opening and a supporting rim around said opening, a relatively thick board having playing surfaces adapted to 55 fit into said frame, said board having a

flange to engage the walls of said frame whereby the board will be held centered in the frame, said board having an offset which in conjunction with said walls form channels when the offset side is uppermost, said 65 offset adapted to engage the rim of said opening when the flanged side of the board is uppermost, said flanged side having a series of pockets formed therein, a ball and projector therefor adapted to project balls 70 into said pockets, said projector consisting of an inclined tube, said projector being pivotally mounted, means for directing the aim of said tube, said means consisting of a slidable member, and means thereon for engaging said tube, a pivoted stand for said tube, said stand being vertically adjustable, and means whereby said frame and stand may be locked together.

14. The described device consisting of a 80 frame having a reversible board, one surface of said board together with said frame forming a ten-pin alley, a ball projector for said alley, said projector consisting of an inclined tube, a vertically adjustable stand for 85 one end of said tube, and means for aiming the outlet end of said tube, said means consisting of a sliding wire connected with one end of said tube.

15. The described device consisting of a 90 frame having a reversible board, one surface of said board together with said frame forming a ten-pin alley, a ball projector for said alley, said projector consisting of an inclined tube, a vertically adjustable stand 95 for one end of said tube, means for aiming the outlet end of said tube, said means consisting of a sliding wire connected with one end of said tube, and means whereby the force of the ball shot from said tube may be 100 regulated.

16. The described game device consisting of a frame having a reversible board, one surface of said board together with said frame forming a ten-pin alley, a ball projector for said alley, said projector consisting of an inclined tube, a vertically adjustable stand for one end of said tube, means for aiming the outlet end of said tube, said 105 means consisting of a sliding wire connected with one end of said tube, and means whereby the force of the ball shot from said tube may be regulated, said means consisting of a telescopic stand for one end of said tube.

In testimony whereof I affix my signature 115 in presence of two witnesses.

ORLANDO W. CRAMPTON.
